UNITED STATES PATENT OFFICE.

WILLIAM PRESTON HOLT, OF WILSON, ARKANSAS.

VENDING-MACHINE.

1,240,717.

Specification of Letters Patent. Patented Sept. 18, 1917.

Application filed October 11, 1916. Serial No. 125,059.

To all whom it may concern:

Be it known that I, WILLIAM PRESTON HOLT, a citizen of the United States, residing at Wilson, in the county of Mississippi and State of Arkansas, have invented certain useful Improvements in Vending-Machines, of which the following is a specification, reference being had therein to the accompanying drawing.

10 The invention relates to a vending machine, and more particularly to the class of liquid filled bottle vending machines.

The primary object of the invention is the provision of a machine of this character 15 wherein bottles filled with liquid can be placed therein, and on the deposit of a coin of a predetermined denomination or value, the machine can be operated for ejecting a single bottle therefrom, the machine being 20 designed for the vending of liquid perfumery in bottles.

Another object of the invention is the provision of a machine of this character wherein the coin, on inserting the same within the 25 machine, will be deposited therein, and should a spurious coin be deposited therein, the same will be ineffective for the operation of the machine.

A further object of the invention is the 30 provision of a machine of this character wherein the construction thereof is novel in form, and to assure the successive delivery of the bottled liquid, singly, on the deposit of coins within the machine, the 35 coin controlled mechanism being positive in operation.

A still further object of the invention is the provision of a machine of this character which possesses simplicity in construction, 40 durability, reliability and efficiency in its operation, and also one which is inexpensive to manufacture.

With these and other objects in view, the invention consists in the features of construction, combination and arrangement of parts, as will be hereinafter fully described, 45 illustrated in the accompanying drawings, and pointed out in the claims hereunto appended.

50 In the accompanying drawings:—

Figure 1 is a side elevation of a machine constructed in accordance with the invention.

Fig. 2 is a top plan view thereof.

55 Fig. 3 is a vertical longitudinal sectional view through the machine.

Fig. 4 is a sectional view on the line 4—4 of Fig. 1.

Fig. 5 is an end elevation.

Fig. 6 is a sectional view on the line 6—6 of Fig. 1.

Similar reference characters indicate corresponding parts throughout the several views in the drawings.

Referring to the drawings in detail, the 65 vending machine comprises a body A, formed with a vertical column 10, and a right angular extension 11, which provides a chamber 12 for accommodating the coin controlled operating mechanism hereinafter 70 fully described.

The column 10 is provided with a glass panel side wall 13, and this column forms a holder for a plurality of liquid filled bottles 14, preferably containing perfumery, 75 which bottles are adapted to be ejected singly, from the column in a manner presently described.

Arranged spaced from the bottom of the column 10 is a horizontal partition 15, which 80 divides the said column into upper and lower chambers 16 and 17 respectively, the latter being designed to accommodate coins deposited in the machine, while the chamber 16 receives the liquid filled bottles 14, to be 85 dispensed from the machine.

Resting upon the partition 15, and communicating with the chamber 16 is a semi-cylindrical delivery trough or chute 18, which is formed at one end with a circular 90 shaped delivery spout or mouth 19, protruding without the body A, and through which is delivered, singly, the bottles 14 containing the liquid perfumery, on the operation of the coin controlled operating mechanism 95 hereinafter fully described.

Arranged within the chamber 12, and adapted to work within the trough or chute 18, which has its inner end opening into said chamber 12, is an ejector arm or slide 20, 100 which, at its end extended within the chute or trough 18, is formed with an ejector head 21, to lie in the path of the bottom end of the bottle 14 resting within the chute or trough 18 of the lowermost one of the series 105 stacked within the column 10, so that the arm or slide 20, when operated, will eject the said bottle through the mouth or spout 19, for the dispensing thereof.

Cooperating with the arm or slide 20, is 110 a plunger 22, which normally protrudes without the extension 11 at one end thereof,

through the guide slot 23 therein, and the inner end portion of this plunger is formed with vertical and horizontal bifurcations 24 and 25 respectively, while the arm or slide 20 is formed with a bifurcation 26, to co-act with the vertical bifurcation 24 in the plunger 22 for receiving the coin therein, when inserted through a coin slot 27, formed in the top of the extension 11, so that on inward movement of the plunger 22, by pushing thereon, the coin deposited will abut the closed ends of said bifurcations 24 and 26, and thereby simultaneously move the ejector arm 20 with the plunger for the ejecting of a bottle from the column 10 without the same.

The bifurcations 25 and 26, in the respective plunger 22 and arm 20, will permit independent movement of the said plunger 22 inwardly, without imparting movement to the arm or slide 20, when a coin has not been deposited within the machine, so that the ejecting arm or slide 20 is ineffective for the delivery of a bottle without the column 10 of said machine.

25 Suitably anchored within the extension 11, below the path of movement of the arm 22, is a coiled expansion spring 28, which acts against an abutment wing 29, on and depending from the plunger 22, to normally hold the plunger extended without the extension 11, and to return the said plunger to normal position after pushing the same inwardly on the deposit of a coin within the machine for the operation thereof.

30 Above the point of anchor of the spring 28 within the extension 11, is a coin rest 30, having a runway 31, communicating with an inclined guide 32, within the extension for directing the coin inserted within the machine.

35 Should a coin of improper size relative to the predetermined sized coin of a given denomination be deposited within the slot 27, it will drop onto the rest 30 and thence fall through the runway 31, and by the guide 32 be delivered into the chamber 17 for deposit therein, without becoming effective for the operation of the arm 20 by the plunger 22 to deliver a bottle 14 from the column 10, and 40 this is due to the extent of the vertical bifurcation 24 relative to the bifurcation 26 in the plunger 22 and arm 20 respectively.

45 However, on the deposit of a proper coin in the slot 27, and the operation of the plunger 22, the bottles 14 will be successfully ejected from the machine, or delivered therefrom.

50 The wing 29 on the plunger and the shoulders 34 thereon, limit the outward movement of said plunger to normal position, as will be apparent.

55 The column 10, at its top, is provided with a hinged lid or cover 35, which, when closed, can be locked in this position in any suitable manner, and access can be had to the column

60 on the opening thereof for replenishing the bottle goods for the dispensing of the series held therein.

65 From the foregoing, it is thought that the construction and manner of operation of the invention will be clearly understood, and therefore, a more extended explanation has been omitted.

What is claimed is:

1. In a vending machine, a body formed with a column and extension, a partition in the column, for dividing the same into chambers, a delivery trough within the uppermost chamber and terminating in a spout without the body, a bifurcated ejector slide movable within the trough for ejecting articles singly therefrom through the spout, a plunger slidably fitted in the extension and having a bifurcation for receiving a coin to position the same relative to the ejector slide, means for automatically projecting the plunger without the extension, and a runway for the coin released by the plunger and slide after the deposit of said coin for delivering the same into the lowermost chamber in the column.

2. In a vending machine, a body formed with a column and extension, a partition in the column for dividing the same into chambers, a delivery trough within the uppermost chamber and terminating in a spout without the body, a bifurcated ejector slide within the trough for ejecting articles singly therefrom through the spout, a plunger slidably fitted in the extension and having a bifurcation for receiving a coin to position the same relative to the ejector slide, means for automatically projecting the plunger without the extension, a runway for the coin released by the plunger and slide after the deposit of said coin for delivering the same into the lowermost chamber in the column, and means on the plunger for limiting the outward movement thereof.

3. In a vending machine, a body formed with a column and extension, a partition in the column for dividing the same into chambers, a delivery trough within the uppermost chamber and terminating in a spout without the body, a bifurcated ejector slide within the trough for ejecting articles singly therefrom through the spout, a plunger slidably fitted in the extension and having a bifurcation for receiving a coin to position the same relative to the ejector slide, means for automatically projecting the plunger without the extension, a runway for the coin released by the plunger and slide after the deposit of said coin for delivering the same into the lowermost chamber in the column, means on the plunger for limiting the outward movement thereof, and a transparent panel forming one wall of the column.

4. In a vending machine, a body formed with a column and extension, a partition in

the column, for dividing the same into chambers, a delivery trough within the uppermost chamber and terminating in a spout without the body, a bifurcated ejector slide within the trough for ejecting articles singly 5 within the trough for ejecting articles singly therefrom through the spout, a plunger slidably fitted in the extension and having a bifurcation for receiving a coin to position the same relative to the ejector slide, means 10 for automatically projecting the plunger without the extension, a runway for the coin released by the plunger and slide after the deposit of said coin for delivering the same into the lowermost chamber in the column, 15 means on the plunger for limiting the outward movement thereof, a transparent panel forming one wall of the column, and an opening cover at the top of the column.

5. In a vending machine, a body formed 20 with a column and extension, a partition in the column for dividing the same into chambers, a delivery trough within the upper-

most chamber and terminating in a spout without the body, a bifurcated ejector slide within the trough for ejecting articles singly 25 therefrom through the spout, a plunger slidably fitted in the extension and having a bifurcation for receiving a coin to position the same relative to the ejector slide, means for automatically projecting the plunger 30 without the extension, a runway for the coin released by the plunger and slide after the deposit of said coin for delivering the same into the lowermost chamber in the column, 35 means on the plunger for limiting the outward movement thereof, and a transparent panel forming one wall of the column, said plunger being bifurcated to co-act with the bifurcation in the slide to prevent operation of the latter by the plunger without the de- 40 posit of a coin.

In testimony whereof I affix my signature.

WILLIAM PRESTON HOLT.
